I. W. WAGNON.

AUTOMATIC RIFLE.

APPLICATION FILED SEPT. 30, 1919.

Patented Nov. 29, 1921.

UNITED STATES PATENT OFFICE.

IRA W. WAGNON, OF CASA GRANDE, ARIZONA, ASSIGNOR OF ONE-HALF TO JOHN F. BROWN, OF CASA GRANDE, ARIZONA.

AUTOMATIC RIFLE.

1,398,452.

Specification of Letters Patent. Patented Nov. 29, 1921.

Application filed September 30, 1919. Serial No. 327,494.

To all whom it may concern:

Be it known that I, IRA W. WAGNON, a citizen of the United States, and a resident of Casa Grande, in the county of Pinal and 5 State of Arizona, have invented certain new and useful Improvements in Automatic Rifles, of which the following is a specification.

My invention is an improvement in automatic rifles, and has for its object to provide 10 a rifle of the character specified, magazine fed, recoil operated, and air cooled, wherein the motive power for the operation of the mechanism is furnished by the recoil of the 15 bolt incident to the explosion, and wherein recoil springs are eliminated.

In the drawings:

Figure 1 is a partial longitudinal section at the magazine;

20 Fig. 2 is a partial horizontal section;

Fig. 3 is a bottom plan view of a portion of the bolt;

Fig. 4 is an end view of the barrel.

The improved gun comprises the usual 25 barrel 1 connected to the frame 2, and this frame carries a compression chamber 3 in alinement with the barrel. The bolt 4 has a head 5 at the end remote from the barrel, and this head moves in the compression 30 chamber, the said head having compression rings, as shown.

The other end of the bolt moves in the reamed out breech portion or cartridge chamber 6 of the barrel, and this end is also 35 provided with compression rings as shown.

The said end has a firing pin 7 and a cartridge guard and ejector 8. The cartridges, indicated at 9, are arranged within a magazine 10 which is detachably connected with 40 the barrel and frame, and which may be released from the barrel and frame by means of a catch 11. The cartridges are arranged in the magazine in inclined position, being inclined at an angle of approximately forty- 45 five degrees, and they are arranged with the bullet end downward.

A follower 12 engages the cartridges remote from the bolt 4, and a spring 13 is arranged between the front of the magazine 50 and the follower, normally acting to press the cartridge toward the breech of the rifle.

An extractor from the magazine is connected with the bolt, the said device comprising a pair of arms 14 which have catches 55 on their inner faces for engaging the rim

of the cartridge in a well known manner, to draw the same out of the magazine and in position to be loaded into the barrel. The bolt 4, the firing pin and the feeding device 14 constitute an integral structure and the 60 compression in the chamber 3 is such that the bolt will not be driven rearwardly until the projectile is at the muzzle of the barrel. At this moment the gas pressure will overcome the inertia of the bolt, and will force 65 the bolt backward far enough to open the chamber to permit the escape of gas. As soon as the pressure is relaxed the compression in the chamber 3 will drive the bolt forwardly.

70 A rod or link 15 is pivoted at one end to the bolt, and the other end passes through a stuffing box 16 in a cylinder 17 arranged just below the compression chamber 3. A piston 18 is connected with the link or rod, 75 the said piston having compression rings, and the piston moves in the cylinder 17. This cylinder 17 and piston 18 constitute a double acting pump, which supplies air for cooling the barrel.

80 It will be noticed, referring to Figs. 1 and 4, that the barrel has a series of radial vanes 19 extending from a collar 20 encircling the same at the breech end and the muzzle of the barrel, the said vanes being of relatively 85 great width and placed relatively close. A tubular member encircles the vanes at the peripheral edges thereof, and thus a series of chambers is provided, extending longitudinally of the barrel from the breech to 90 the muzzle.

The pump 17-18 delivers to these chambers through the collar 20 which is a distributing collar. The chamber communicates with the collar by means of a pipe 21, and 95 the pipe has openings near the ends of the cylinder. The cylinder has also a suitable check controlled inlet 21a.

100 The rifle is armed by means of a charging handle 22 connected with the bolt and extending laterally through the frame. The bolt is held in charging position by means of a trigger pawl 23 which engages a catch 24 on the bolt when the bolt is drawn rearwardly far enough to be behind the trigger pawl. The trigger pawl is connected to the trigger 24a by means of a link 25 and a spring 26 co-operates with the trigger and the pawl, acting to retain the pawl in holding position until released by the trigger. 110

The link 25 is fulcrumed on a bracket 27 in the frame 3.

- 5 The rearmost cartridge in the magazine is grasped by the arms 14 and is drawn rearwardly by the bolt when the rifle is charged. The cartridge rides upon the inclined end of a carrier 28 which is arranged within the frame in rear of the magazine. This carrier is normally pressed upward by a spring 29
 10 and is held downward by the piston rod 15, when the bolt is in forward position. When the bolt is drawn rearwardly into charging position and the catch 24 is engaged with the pawl 23, the carrier, as soon as the bolt has moved behind the same, will lift the cartridge upwardly, and the said cartridge will be centered in position to enter the chamber 6 by means of a detent 30 just above the carrier.
 15 20 When the trigger is operated to release the pawl, the compressed air in the chamber 3 will move the bolt forwardly, and the cartridge carried by the carrier will be driven into the chamber 6. The pin 8 is spring
 25 mounted to yield under a predetermined pressure. This spring is strong enough to move the cartridge ahead of the firing pin, so that the firing pin does not engage the primer until the cartridge has been seated in the
 30 cartridge chamber and cannot be moved farther by the spring pressed pin. The pin now yields and the firing pin enters the primer, detonating the cartridge. When the trigger

is held down, that is, with the pawl in released position, the rifle will fire continuously, being operated by the recoil. 35

I claim:

1. In combination, in an automatic rifle, a barrel having a compression chamber in alignment therewith, a bolt having a plunger 40 working in the compression chamber and a portion extending into the barrel when in operative position and sealing the same, means controlled by the movement of the bolt for feeding cartridges in succession to 45 the barrel, said bolt having a firing pin rigid therewith, and a spring held cartridge guard extending beyond the firing pin for insuring the insertion of a cartridge before the firing pin engages the same. 50

2. In combination in an automatic rifle, a barrel, a magazine below the barrel, a bolt moved in one direction by the recoil, a compression device for returning the bolt, said bolt having means for withdrawing a cartridge from the magazine, means coöperating therewith for moving the cartridge into alignment with the barrel, and a spring supported cartridge engaging pin on the bolt for moving the cartridge in the barrel in 60 advance of the firing pin. 55

IRA W. WAGNON.
